COLLOIDAL MILL AND SYSTEM OF
CONTROL THEREFOR

Oscar A. Ross, New York, N. Y.

Application December 1, 1927. Serial No. 236,981

37 Claims. (Cl. 83-8)

This invention refers to colloidal mills and more particularly to that type of colloidal mill employed for the combined dispersing grinding and mixing of solids with liquids whereby a colloidal suspension of the solids in said liquids obtains.

One object of this invention is to provide a colloidal mill wherein a minute adjustment of the dispersing rotors may be obtained whereby a sensitive control of the size of the colloids in suspension may be obtained.

Another object is to mount the aforesaid rotors and the driving motors therefor in a manner whereby a minimum of distortion of the relative dispersion faces of said rotors will obtain.

Another object to provide a colloidal mill wherein the material to be dispersed will be so dispersed in stages, providing a rest, or stabilizing period between each stage during which said material may be cooled and allowed to readjust its physical structure before being again treated in a succeeding stage of dispersion.

Another object is to provide a colloidal mill having dispersion rotors which are hollow and through which water or other liquid may be circulated for the purpose of cooling or heating the materials to be dispersed.

Another object is to provide a colloidal mill having rotors wherein the materials to be dispersed are substantially moved radially with respect to the axis of rotation of said rotors, however, by a novel arrangement providing a dispersion surface substantially in excess of the actual radial distance between the innermost and outermost dispersion surfaces of said rotors.

Another object is to provide a colloidal mill wherein the materials to be dispersed are fed through a stationary hollow tube to the point of initial dispersion, in this manner preventing any tendency for separation or segregation of pre-mixed materials fed to said mill due to centrifugal action if said tube were rotated.

Another object is to furnish a novel system of automatic control for the cooling or heating liquid supplied to the aforesaid rotors whereby a substantially uniform temperature is maintained during the dispersion of material; also an automatic alarm system whereby an operator is informed of abnormal conditions arising during said dispersion, and, in event of lack of proper attention thereafter, will cause the motors driving said rotors to be stopped whereby possible damage to said material and rotors will be prevented.

Another object is to furnish novel means for

driving material dispersion rotors whereby the material dispersion passageway therebetween will be restrained to unusual uniform dimension circumferentially thereof whereby a maximum flow of completely dispersed product may be obtained from a colloidal mill. The applicant has discovered that when material dispersion rotors are driven by belts, ropes, or similar drives placed at one side of the mill, the transverse stresses on the rotors due to the torque of the belts causes a deflection of the axes of the rotors thereby also deflecting the material dispersion members in this manner producing a comparatively small material dispersion passageway between the members on the torque producing side of the mill and a comparatively large passageway on the diametrically opposite side thereof. This distortion may even act to cause rubbing of the members on the torque side of the mill. Such non-uniformity of the passageway tends to produce non-uniformly dispersed finished product.

Another object is to furnish material dispersion rotors the shaft portions of which are comparatively large in diameter and of comparatively rugged construction whereby the "whipping" and torsional stresses are minimized, thereby further assuring a uniform width of the material dispersion passageway between the rotors.

Other objects and advantages will appear as the description of the invention progresses, and the novel features of the invention will be pointed out in the appended claims.

This invention consists in the novel construction and arrangement of parts hereinafter described, delineated in the accompanying drawings, and particularly pointed out in that portion of the instrument wherein patentable novelty is claimed for certain and peculiar features of the invention, it being understood that, within the scope of what hereinafter thus is claimed, divers changes in the form, proportions, size and minor details of the device and system of control therefore may be made without departing from the spirit of, or sacrificing any of the details of the invention.

In describing the invention in detail, reference is had to the accompanying drawings wherein I have illustrated embodiments of my invention, and wherein like characters of reference designate corresponding parts through the several views, and in which:—

Figure 1 is a sectional part view of one form of colloidal mill and is taken on line I—I of Figure 4 and Figure 2, is a side elevational view of a complete mill and is taken on line II—II of Fig-

100

105

110

ure 3, and Figure 3 is an end view of the same taken on line III—III of Figure 2, and Figure 4 is a part sectional, part elevational view of the same mill taken on line IV—IV of Figure 1, and Figure 5, is a part sectional view of one form of dispersion rotors, and is an enlarged view of the similar rotors shown in Figure 1, and Figure 6, is a similar part sectional view of a modified form of rotors, and Figure 7, is still another part 10 sectional view of a modified form of rotors, and Figure 8, is a sectional view of the rotor adjustment apparatus, and is taken on line VIII—VIII of Figure 1 and, Figure 9 is a part sectional view of a modified form of colloidal mill, and Figure 10, is a diagrammatic view of a control system for colloidal mills, and Figure 11, is another diagrammatic view of a system of dispersion with colloidal mills.

Referring to Figures 1, 2, 3, 4 and 5, the colloidal mill 1 comprises base 2 on which are suitably secured dispersion rotor unit 3, hereinafter termed rotor unit, motor units 4—4, micrometer adjustment and thrust bearing units 5—5, hereinafter termed micrometer units, and cooling 25 liquid and material inlet units 6—6. Figure 1 represents substantially a sectional view of the right hand one half of a complete mill as shown in Figure 2.

Rotor unit 3 comprises rotor housings 35 and 1 30 matingly related and are secured together by bolts 9—9. Each housing, as 35 and 7 have a bearing supporting bore 8 adapted to radially support but permit axial movement of the outer race of ball bearing 10; and annular cooling 35 liquid reservoir 11, receiving said liquid through orifices 12—12 of gland 13 and discharging said liquid through orifice 14 into pipe 15.

Bearing 10 is oiled by cup 16, washer 17 acts as a dirt guard therefor and orifice 18 drains 40 plus oil therefrom. Housing 35 has a finished material orifice 19 into which discharge pipe 20a is secured. Each of said housings have a threaded sleeve portion 20, receiving gland nut 21 adapted to restrain packing 22, and gland 13 to the left 45 against packing 23, gland 13 floating between said packings but guided by said sleeve portion. Said housings also have a male mating face 24 adapted to non-rigidly support motor ventilating rings 25—25 having male flanges 25a and female flanges 25b.

Motors 4—4, comprise stator 26, having frames 27—27 suitably secured to base 2 and provided with female mating faces 28—28 adapted to non-rigidly receive the male ends 25a—25a of ventilating rings 25—25, also driving rotor 29, rigidly secured to tubular extension 106 of dispersion rotor units 91 and 92. The motors 4—4 may be electric motors of any well known type and as shown is standard General Electric three phase induction motors receiving current through cable 114 passing into conduit 115.

The micrometer units 5—5 comprise housing 32, suitably secured to base 2, the male flange 33 of which is adapted to non-rigidly receive 65 female flange 25b of ventilating ring 25 and the female flange 34 of the cooling liquid and material inlet unit 6, secured by bolts 36—36. Said units also comprise tubular portion 37 adapted to receive thrust bearing unit 38, said last named unit, having circumferential and axial movement in said tubular portion, the circumferential movement being caused by rotation of worm 39, mounted on shaft 40 operating in bearings 41 and 42, and between which are also ball thrust bearing 43—43, bearing 41 being permanently

secured in boss 44 by threads 45, and bearing 42 being adjustably secured in boss 46 by threads 47 and lock nut 48 (see Figure 8), said worm acting on teeth 49 and causing circumferential movement of said unit and said last named 80 movement causing axial movement of said unit by screwing in or out of threads 50. For example, the normal size of mill 1 is preferably approximately three times the dimensions showing in Figure 1, therefore assuming a 12 pitch tooth there would be approximately ninety teeth, as 49 and assuming sixteen pitch threads as 50, one revolution of worm 39 would axially advance unit 38, .00007 inches; dial 51, secured to boss 44, and over the face of which pointer 52, secured to head 53 of shaft 40, is adopted to travel is preferably divided into one hundred graduations and therefore each increment of movement of said pointer will advance said unit .000007 of an inch. Further description in connection with the rotor units 91 and 92 will disclose that their construction will permit of an even finer adjustment between their respective dispersing surfaces. Tubular portion 37 is also adapted to support bearing 55 in machined bore 56, the outer 100 race 57 of which has axial movement in said bore, and is protected against foreign matter by washer 58 rigidly secured in said bore.

Thrust bearing unit 38 comprises shell 60 having stop flange 61 and axial adjustment flange 62 105 threaded externally to screw in threads 50, and internally to receive lock nuts 63—63 adapted to clamp stationary thrust washers 64—64 between sleeve 65 and against stop flange 61. Said unit also comprises rotating thrust collar 66 110 snugly fitting over machined sub-extension 108 of rotor unit 91 and is rigidly secured to said extension by lock nuts 67—67 acting to clamp said thrust collar, washer 68 and inner race 69, of bearing 55 against shoulder 109 of said rotor 115 unit. Balls 88 interposed between collar 66 and collars 64—64 act to move collar 66 and its depending parts, as rotor 91, axially, when, and as unit 38 is similarly axially moved.

Cooling liquid and material inlet unit 6 comprises housing 72 having male flange portion 73 adapted to mate with female portion 34 of unit 5; machined boss 74 in which one end of water tube 75 is rigidly secured; tubular portion 76 machined internally to permit axial movement of 120 one end of material tube 77 and threaded externally to receive nut 78 adapted to restrain gland 79, supporting rotatable fitting 80 (see Figure 4), terminating in pipe 81, against packing 82. Housing 72 also comprises water inlet 130 chamber 83 communicating to pipe 84 through orifice 85. Material tube 77 is restrained against circumferential movement by pin 86 secured thereto and adapted to have axial movement in slot 87.

Radially supported by bearings 10—10 and 55—55 and axially guided by thrust bearing units 38—38 are dispersion rotor units 90 and 91 hereinafter termed rotors, said rotors being similar in form except as to dispersion disks 92 and 93. 140 Said rotors comprise housing 94 having male flange 95 adapted to mate and be suitably secured to female flange 96 of dispersion disk supporting plate 97, also the tubular portion 98, the shoulder 99 of which is machined to rigidly receive inner race 100 of bearing 10 and is drilled to receive one end of studs 101—101 interposed between said portion and plate 97 and adapted to support cooling liquid guide baffle plate 102, the center tubular portion 103 of which is adapt- 145 150

ed to act as a bearing guide for the exit end 104 of water tube 75. Tubular portion 98 also has radially disposed cooling liquid outlet orifices 105—105 adapted to pass the cooling liquid to the openings 12 of gland 13 and thence to chamber 11 and pipe 15, said rotor housing also has reduced tubular extension 106 to which motor rotor 29 is suitably rigidly secured; also a second reduced tubular portion 108 and shoulder 109 to which as hereintofore described is secured bearing 55 and thrust collar 68; also a gland 110 adapted to restrain packing 111 against cooling liquid tube 75, by action of gland nut 112.

To the exit end 116 of material delivery tube 15 77 is rigidly secured collar 117 (Figures 1 and 5) the face 118 of which is adapted to bear on face 119 of gland nut 120 rigidly secured to orifice 121 in dispersion disk support plate 97, springs 122—122 acting to cause said faces to engage 20 with each other.

Dispersion disks 93 and 94 comprise continuous circumferential beveled mating projections 125—125 adjoining each other, each having a pair of dispersion faces 126 and 127. The base 25 of each of said adjoining projection is joined by a groove, as 128. At the apex of each of said projections is another groove 129, rigidly secured in which, is a continuous band or baffle ring 130. The material to be treated enters at the inner 30 groove 131 and leaves at the peripheral groove 132.

Referring to Figure 6 showing modified dispersion disks 135 and 136, the dispersion faces 137 and 138 are all arranged substantially in a radial plane, however their continuity is interrupted by grooves 138a—138a and continuous baffle rings 139—139 rigidly secured in grooves 140—140. The material to be dispersed enters at groove 141 and leaves at peripheral groove 40 142.

Referring to Figure 7 showing still another modified form of rotors 145 and 146, the projections 147—147 are similar to projections 125, however are angularly more acute, in this manner not only increasing the lineal dispersing surface for a given radial distance, but also permitting the omission of baffles, as 130, the apex 45 148 moving in groove 149 acting as said baffles. The material enters at groove 150 and leaves at groove 151.

Referring to the modified form of colloidal mill 159, shown in Fig. 9, the rotor housings 160 and 161, the latter not shown, are similar to housings 7 and 35, however are modified to omit 55 the cooling liquid receiving chamber 11 and the inclusion of a modified micrometer unit, as 162, the machined flanges 163 and 164 of which are adapted to snugly enter machined bore 165 of rotor housing 160 and is adapted to be allocated by dowel screw 166 locked by nut 167. Micrometer unit 162 also comprises a thrust bearing unit 168. Similar in structure and function to unit 38, and actuated by a worm as 39, the revolving thrust collar 169 of which is clamped against spacing collar 170 impinging against the inner race of bearing 10, by lock nuts 171—171.

The bearing and gland unit 175, supplants the micrometer unit 5 of Figures 1, 2, 3 and 4, and comprises housing 176 having male flange 177 adapted to non-rigidly mate with one end of frame 25, and female flange 178 adapted to mate with male flange 73 of cooling liquid and material inlet unit 6. Housing 176 also comprises tubular portion 180, radially supporting the outer race of 75 bearing 10, in machine bore 183 but permitting

axial movement thereof between protection washers 181 and 182 secured in said bore. Said housing also comprises internally machined and threaded gland portion 184, supporting gland nut 185 adapted to restrain packing 186 against rotor unit 195. Orifice 187 acts to drain surplus oil and foreign matter from bearing compartment 188.

The inner race of bearing 10 of unit 175 is rigidly secured to sleeve 189, washer 190 rigidly secured thereto acting to clamp said bearing against shoulder 191, said sleeve having slots as 80 192 adapted to engage pins 193 and restrain said sleeve bearing 10 and washer 190 to rotate with rotor unit 195. Housing 176 is also provided with chamber 179 adapted to receive the cooling liquid 85 from orifice 199 of rotor unit 195.

Dispersion rotor units 195 and 196, the latter not being shown, are similar to rotors 91 and 92, however are modified by omission of cooling liquid outlet orifices 105—105, reallocation of collar 169 of the thrust bearing unit, as 168 on tubular portion 197, and the omission of gland 110, the tubular extention 198 being maintained substantially the same internal diameter as portion 197. The external diameter of said tubular portions 100 are comparatively minutely graduated, the largest step receiving inner race of bearing 10, the next smaller collar 169, the next rotor 179, and the last bearing sleeve 189.

Referring to Figure 10, material to be dispersed 105 in mill 1 entering by pipe 81 may be supplied from pipe 204 by pump 200, driven by motor 201 controlled by speed control unit 202, actuated by lever 203, the lowering of said lever decreasing said speed and raising of said lever increasing 110 said speed.

Cooling or heating liquid is supplied to mill 120 through pipe 84 as will be more fully hereinafter described. After the cooling or heating liquid hereinafter termed "water" has passed through mill 1, as will also be more fully hereinafter described, it is withdrawn through pipes 15—15 by pumps 205—205 driven by motors 206—206 said pumps acting at all times to develop a partial vacuum within the water circulating system 125 of said mill. From pumps 205—205 said water is conveyed through pipes 207—207 to thermo-control units 208W—208W comprising housing 209 having intake orifice 210 receiving pipe 207, and outlet orifice 211, connected to discharge pipe 130 212, and to the bottom of which is secured one end of sylphon 213, the other or one end being restrained downwards by spring 228, adjusted by threaded sleeve 229 and has secured thereto, rod 214, insulatively supporting contact dish 215 restrained upwardly by spring 216 against collar 217 secured to said rod, said rod also insulatively supporting contact disk 218 restrained downwardly, to closed circuit position, by spring 219 arranged between said last named disk and collar 135 220 secured to said rod, collar 221, also secured to said rod being adapted to raise said last named disk upon a predetermined upward movement of said rod. Cover 222 suitably secured to housing 209 acts to seal chamber 223 and through 140 sleeve 229 acts as a guide for rod 214.

The motors 4—4 of mill 1 are supplied with energy from starting boxes 225—225 of known form and having no voltage relays 226—226.

The finished material from mill 1 passes 145 through pipe 20 to a unit 208M, the upper end of rod 214 of which, is secured by sleeve 234 to stem 230 of valve 231 receiving water through pipe 232 and delivering said water to mill 1 through pipe 233 with valve 231 open. Valve 231 150

is adapted to open as rod 214 is raised and closed as said rod is lowered. Said valve preferably has a leakage groove whereby a comparatively small quantity of said liquid continuously passes therethrough to mill 1. Said unit also has one end of bifurcated lever 238 pivotally secured to collar 220 and the other end pivoted to rod 203 adapted to actuate speed control units 202—202, said lever is pivotally mounted on pin 236, said material discharges through pipe 237.

The operation of applicant improved colloidal mill is as follows:—referring to Figures 1, 2, 3, 4, 5 and 10 rotors 90 and 91 are rotated in reverse directions, the speed being selected for the particular materials which said mill is to treat, said speed being preferably 1800 R. P. M. when dispersion conditions will so permit.

The material to be treated may be supplied in two forms, for example if an enamel, the pigment may be supplied mixed in a light solvent to one end of the mill through pipe 81 and the varnish or body material through pipe 81 of the other end of said mill, said materials passing through fittings 80—80 into interior of material tube 77 and thence axially as shown by arrows to chamber 89 and thence radially to groove 131 where dispersion between surfaces 126 and 127 begins, the material finally reaching the first or innermost cooling and stabilizing, hereinafter termed "stabilizing", groove 128, where a comparatively slow movement of the material obtains, baffle ring 130 causing said material to take a comparatively long path whereby its heat or cold may be absorbed by the material of disk 94, and the highly agitated solid particles allowed to stabilize their molecular structure, and whereafter it again is further dispersed by another pair of dispersion faces, as 126 and 127 and whereafter it again passes to another stabilizing groove, as 128 and is again "stabilized" before the succeeding dispersion stage, eight such stabilizing and nine such dispersion stages being shown as forming part of the structure of dispersion disks 93 and 94, said material finally leaving by groove 132 from whence it is thrown against the interior of housings 7 and 35 and finally gravitates to chamber 19 and pipe 20 whereafter it passes past valve 235 to thermount 208 to and around it sylphon 213 acting on the vapors contained therein as will be more fully hereinafter described.

It will be noted that the material during the dispersion process has moved diagonally radially, and whereas the material exists from dispersion disks 93 and 94 on substantially the same radial plane as when it entered said disks, it has moved over a lineal dispersion distance substantially in excess of the distance represented by a straight radial line between said material exit and entrance.

Many materials evolve more or less heat in dispersion as heretofore described, whereas in other materials it is necessary to add heat to or maintain a substantially uniform heat of said material during the dispersion process.

To accomplish such heating or cooling, water or other cooling liquid or gas, hereinafter termed "water", is fed as will be more fully hereinafter described through pipes 84—84 to chambers 83—83 and thence to the interior of cooling liquid tubes 75—75 surrounding material tubes 77—77, as shown by the several arrows, thereafter passing into annular chamber 123 between dispersion disk supporting plates 97—97, thence outwardly radially and around the outer edge of baffle plate 102, thence inwardly radially through

chamber 124 into the interior of tubular portion 98 where the centrifugal action caused by the rotation thereof, causes said water to assume a tubular column as shown by dash lines 133—133, and whereby said water is restrained outwardly 80 through openings 12—12 in glands 13—13, finally passing into chambers 11—11, and pipes 15—15 to pumps 205—205 and thence to thermounts 208W—208W as will be more fully hereinafter described.

It will be noted that annular chamber 123 is tapered, this taper being preferably proportioned whereby the volume of the water at any given radial distance will be substantially uniform as it is moved radially outwardly, in this manner assuring that the exposed surfaces of dispersion disk support plates 97—97 will be in contact with said water whereby a maximum of heat or cold may be absorbed therefrom for the purpose of thermostatically acting on the material being ground by dispersion disks as 93 and 94; 135 and 136 or 145 and 146, the cooling or heating action of said water being communicated through the metal of plates 97—97 to the metal, or other material of said dispersion disks and thence to 100 said material being ground, or stabilized, a portion of said cooling, or heating action being also communicated through the flanges 95 and 96 of rotor housings 94—94 and said plates.

The gland 110, packing 111 and nut 112 act 105 to prevent air being drawn into the interior of rotor housings 94 and 95 and thence to pipes 15—15.

The gland 13, packings 22 and 23 and nut 21 act to likewise prevent air entering chambers 110 11—11 and pipes 15—15 by action of pumps 205—205.

The dispersion rotor units 91 and 92 are adapted to be moved axially by the fitting of a suitable key over the head 53 of shaft 40, and rotation of 115 said shaft and worm 39, in this manner causing rotation of one of thrust bearing units, as 38, the rotation of said units in threads 50 causing an axial movement of said unit, said movement being communicated through balls 88—88 to thrust 120 collars 66—66 rigidly secured to said rotor units, whereas, as heretofore described, each increment of movement of pointer 52 is adapted to cause .000007 inch axial movement said thrust bearing units and therefore a similar movement of said 125 dispersion rotor units, the actual variation of the lineal distance at right angles to the dispersion surfaces, as 126 and 127 is substantially less, this variation being proportional to the sine of the angle formed by the axis of rotation of said 130 rotors and said surfaces.

Referring particularly to Figures 10 and 11 showing applicant's novel control system for colloidal mills, the materials to be dispersed may be supplied by gravity from a reservoir not shown or 135 from a primary colloidal mill, as 1A (Figure 11) entering mill 1, assumed to be in operation, through pipe 224 adapted to be controlled by valve 234, or, may be supplied by pumps, as 140 200—200, leaving mill 1 by pipe 20, adapted to be controlled by valve 235 and passing to and through thermocontrol unit 208M and thence to discharge pipe, or reservoir 237. As said material passes through thermocontrol unit 208M 145 the temperature thereof is adapted to act on sylphon 213 therein, an increase of temperature of said material acting to raise rod 214 and its depending parts including stem 230 of valve 231.

The tension of spring 228 acting on the free 150

end of sylphon 213, is adjusted by sleeve 229 whereby the rod 214 and its depending parts remain substantially as shown in the drawings when the finished material passing through thermo-unit 208M is of the desired temperature. If for any reason said temperature should rise, the liquid, or vapors in sylphon 213 will be expanded, thereby causing rod 214 and its depending parts to move upwardly until contact disk 215 establishes a circuit as follows:—

Alarm circuit

from positive energy to wire 240, disk 215, wire 241, alarm 242 and wire 243 to negative energy, 15 in this manner calling attention to an attendant of an abnormal condition in mill 1. If said attendant fails to observe said alarm and correct said abnormal condition, and if for any reason said condition becomes more abnormal and 20 whereby said temperature of said material is still further raised, a further expansion of said liquid or vapors in sylphon 213 causes a further upward movement of rod 214 and its depending parts, and whereby collar 221 is caused to raise 25 contact disk 218, in this manner interrupting the following circuit:—

No voltage relay circuit

from positive energy, wire 244, disk 218, wire 245, 30 disk 218 of right hand thermo-unit 208W, wire 246, disk 218 of left hand thermo-unit 208W, wire 247 and wires 248 and 249 to no voltage relays 226—226 in multiple, and thence to negative energy; as this circuit is opened the no 35 voltage relays 226—226 act to stop motors 4—4 of mill 1 in known manner and the dispersion process will stop, and before said mill can again be placed in operation it will be necessary to manually operate starters 225—225 in known manner.

40 The cooling water discharging from pipes 15—15 is similarly adapted to control mill 1 by thermo-units, as 208W—208W, the water discharged into said pipes being passed to and through said units by pumps 205—205 and thence 45 to waste pipes, or reservoirs 212—212. Again assuming mill 1 to be in normal operation, and the water discharged by pipes 15—15 to be of normal temperature, the rods 214—214 of said units and their depending parts will be substantially 50 as shown in the drawings. If for any reason an abnormal condition arises in said mill and whereby the temperature of said water is abnormally increased, either one, or both rods 214 will move upwardly thereby causing disk 215 to 55 establish the hereintofore described "alarm circuit" to be sounded calling attention to said abnormal condition and, should the attendant fail to remedy the cause for said abnormality, a further predetermined increase of temperature of 60 said water will act to raise one, or both contact disks 218—218 of said units, thereby opening the aforesaid "no voltage circuit" and motors 4—4 will both be stopped, and must be manually started before said mill can again be placed in 65 operation.

The cooling water to mill 1, is preferably supplied to pipes 84—84 by a valve as 231 adapted to vary the flow of said water to said mill to compensate for ordinary variations in temperature 70 of the water supplied to said mill, for example, a slight increase of temperature of the incoming water supplied by pipe 233 to pipes 84—84 will tend to cause a slight increase of temperature of the finished material issuing from 75 pipe 20, and therefore will cause a slight upward

movement of rod 214 of thermo-unit 208M sufficient to slightly further open valve 231, but not sufficiently to establish the "alarm circuit" by disk 215, or open the "no voltage circuit" by raising disk 218 of said thermo-unit.

80 Thermo-unit 208M is also adopted to control the quantity of material to be supplied to a colloid mill, as 1, by lever 238 and rod 203 adapted to actuate speed control units 202—202, for example, if the temperature of the finished material passing through said unit is lowered, rod 214 is moved downwardly and rod 203 upwardly, in this manner causing control units 202—202 to increase the speed of motors 201—201 driving pumps 200—200 and therefore more raw materials will be supplied to said mill, and conversely as said temperature is increased, rod 203 is lowered and motors 201—201 slowed down to decrease said supply of raw materials to said mill.

85 Referring particularly to Figure 11 showing a process for dispersing materials by colloidal mills, as for example paints, or enamels, the colloidal mill 1A is adapted to receive pigment to be dispersed through material inlet pipe 81L, and a solvent or thinner having a high affinity therefore through pipe 81R, whereafter said pigment is dispersed in said solvent in said mill the purpose being primarily to reduce said pigment to colloidal state in suspension in said thinner or solvent, whereafter said colloidal mixture passes through pipe 20 to a thermo-unit, as 208M, and pipe 224 to material inlet 81L of colloidal mill 1B whereas the paint, or enamel body, as oil, or varnish, is fed to the similar pipe 81R of said last named mill, said mixture and said oil, or varnish being further dispersed by said last named mill, and whereafter the finished product, as for example paint, or enamel, passes through pipe 20 and thermo-unit 208M to pipe or reservoir, as 250 for distribution, or further treatment, for example, with certain pigments it is desirable to add a surplus of thinner, or solvent, during the primary dispersion stage in mill 1A. Under such conditions, and after the such finished product issues from pipe 250, it is further desirable to remove said surplus thinner or solvent by driving said solvent off by artificial evaporation, or partial distillation, simultaneously recovering said solvent in a manner similar to that shown in Patent #1,345,083 issued to Gerli and Ross on 110 June 29th, 1920.

115 Whereas not shown, it is understood that mills as 1A and 1B are supplied with suitable controls apparatus and circuits therefor, as shown in Figure 10.

120 Whereas thermo-units 208W and 208M have been shown as acting to prevent a rise in temperature beyond a predetermined limit, it is obvious that said units may be modified whereby sylphon 213 may be made to raise rod 214 as the free end thereof is lowered by lowering of temperature of the finished material passing therethrough, in this manner assuring that a colloidal mill as 1 will be supplied with conditioning liquid of not less than a predetermined temperature.

125 Whereas for clearer illustration the thermo-units 208W and 208M have been shown as having sylphon 213 directly acted upon by the liquids or material passing through said units, sylphon valves of known form may be employed and the "thermostatic bulbs" therefor may be arranged in the outlet flow of said finished material, and said water.

130 The dispersion rotors as 93 and 94; 135 and 136; and 145 and 146 are preferably of hardened 135

steel and the dispersion surfaces thereof may be plated or covered with an even harder substance, as for example chromium. Due to the high rotative speeds when dispersing, the liquid portions 5 of the material to be treated adheres to the dispersion surfaces and acts as an insulator preventing abrasion, or substantial wear of said dispersion surfaces, any grinding or reduction of the solids particles into smaller particles if non-10 current with dispersion being accomplished by the collision of said particles during transit between the dispersion surfaces as 126 and 127 as the dispersion action is accomplished.

The dispersion disks shown in Figure 6, are 15 preferably employed where the proportion of actual grinding, or reduction of coarser materials may not be as important as a thorough dispersion of the solids and liquids, whereas the dispersion disks shown in Figure 7, are preferably employed 20 when exceedingly fine pigments are to be more thoroughly dispersed whereby the pigment particles are completely suspended in the liquid in colloidal form.

If desired the stabilizing grooves, as 128, 138 or 25 149 may be made deeper as they progress outwardly as shown by the dotted grooves 152—152, the modified baffle rings 153—153 being made correspondingly wider as shown in the dotted form. Further, said grooves may be made progressively 30 deeper beginning with the innermost groove to the outermost, the latter being the deepest, in this manner permitting progressively greater stabilizing of the active material as it moves outwardly during the dispersion process. It is to be noted that the circumferential speed of the 35 outer dispersion surfaces, as 126 and 127 is in excess of the similar speed of the inner of said surfaces. When dispersing certain materials the heat evolved in the dispersing process is likewise 40 progressively increased as the active material moves outwardly and the absorption thereof may be progressively assumed by the hereintofore mentioned progressively arranged deeper grooves as 152 and the progressively arranged wider rings 45 as 153.

By the term treatment, dispersion "grinding and or mixing" is implied that the solid materials may be simultaneously dispersed and ground in the liquid during the dispersion action. The 50 particles of some pigments, as for example, certain lamp blacks, are structurally so fine that the important accomplishment is to isolate each and all of said particles one from another and surround said isolated particles with a liquid to produce a colloidal suspension thereof. In the treatment of such materials, dispersion only occurs, whereas in coarse pigments some grinding occurs.

Water will normally seek its own level whether by gravity or centrifugal action. It will be noted 60 that the water entering chamber 123 from water tube 75, enters at a lesser radius than the water leaving chamber 124 and passing to tubular portion 98 of grinding rotor 91, therefore, centrifugal action assumed, and speaking in terms of gravitation, the higher level of the water in chamber 123 will act to restrain the water in said chamber to pass to chamber 124 as shown by the arrows whereafter centrifugal action again assumed, it passes in tubular form to openings 105—105; 65 12—12 and chamber 11 to discharge pipe 15 the partial vacuum established by pumps 205—205 assisting in this action.

Referring to the modified form of colloidal mill 159, shown in Figure 9, the material to be treated 75 is supplied to, is treated, and leaves said mill in

the same manner as hereintofore described in connection with Figures 1, 2, 3, 4 and 5.

The cooling, or heating water is likewise supplied to said mill in the same manner up to and including chamber 124, whereafter said water moves as a tubular column, centrifugal action being assumed, along tubular portions 197 and 198 of grinding rotors 195 and 196 leaving at openings 199—199 thereafter passing to chambers 179—179 and thence by gravity to discharge pipes 15—15 as shown by the several arrows.

The axial movement of rotors 195 and 196 for dispersion adjustment is accomplished by rotation of worm 39 in a similar manner as hereintofore described in connection with Figures 1, 3 and 8, the rotation of said worm acting on teeth 172 of thrust bearing unit 168, causing rotation thereof and through threads 173, a simultaneous axial movement thereof, said axial movement acting through balls 174—174 to cause axial movement 95 of thrust collar 169 rigidly secured to said dispersion rotor.

The driving motor 4 having rotor 159 is similar to motor 4 and rotor 29 of Figures 1 and 2, however rotor 159 has a larger bore to accommodate 100 the larger tubular section 198 of grinding rotors 195 and 196.

It is to be noted that, a bearing as 10, has been placed as closely adjacent the dispersion faces of rotors 195 and 196 as substantial structure will 105 permit, also that thrust bearing unit 168 has likewise been placed as close to said bearing as substantial structure will permit, in other words the radial dispersion plane and the thrust bearing adjustment planes are comparatively close 110 together. Such an arrangement is desirable when extremely close regulation of the quality of the finished material is desired. It is to be noted that by placing the said thrust bearing unit as closely adjacent the radial dispersion plane as 115 possible, a minimum of axial structure, as metal, obtains between said unit and said dispersion faces, and therefore a minimum of expansion or contraction of said structure will obtain due to temperature variation thereof which might cause 120 a variation of the distance between said dispersion surfaces and therefore a variation in the quality of the finished material ground thereby.

By the novel arrangement of securing the driving elements, as 29—159 of the motors 4 directly 125 to the rotors, as 90—91 and 195—196, the torque applied by said driving elements is wholly circumferential, therefore no radial deflection of said rotors will occur to produce distortion of the material dispersion passageway between said 130 rotors. Said passageway distortion is further minimized by the comparatively large diameter and rugged construction of the shaft portions of the rotor members 94—95 and 195—196 thereby substantially annulling the "whipping" and torsional deflections thereof.

By the term "stabilizing" is also included the absorption and dispersion of ionization of the solid particles during the material dispersion process. It has been reasonably established that continuous collision of colloids tend to produce ionization 140 thereof, and under which condition said colloids may unite in crystalline formations and produce undesirable and noticeable particles in the finished products.

If desired the baffle rings as 130 or 153 may be insulatively supported and electrical energy supplied thereto for the purpose of still further dispersing said ionization.

What I claim is:—

1. A colloidal mill comprising in combination; relatively rotatable material treatment rotors, dispersion faces formed thereon in concentric rows thereon, the rows of one rotor being arranged in dispersion relation to the rows of the other rotor, non-material dispersion advancing passageways formed in concentric rows on the rotors alternately with the dispersion faces, the dispersion faces and the passageways being arranged whereby the material is advanced from one set of dispersion faces to a passageway in one rotor alternately with advancement thereof from similar faces to a passageway in the opposite rotor, means for rotatably supporting the rotors, means for rotating the rotors relatively, means for supplying material to the dispersion faces, and means for conveying the treated material discharged by the rotors to the exterior of the mill. 80
2. A colloid mill comprising in combination; relatively rotatable material treatment members positioned to form a material treatment passage therebetween, dispersion faces formed thereon in concentric rows, the rows of one member being arranged in juxtaposition to similar faces of the other member whereby the material treatment passageway is formed therebetween, grooves formed in one of the members arranged in concentric rows alternately between the dispersion faces, annular baffle members formed on the other material treatment member extending into and bifurcating the grooves whereby material advancing and stabilizing passageways are formed alternately between the rows of dispersion surfaces, means for rotatably supporting the material treatment members, means for rotating the members relatively, means for supplying material to the material treatment passage way for treatment, and means for conducting the treated material therefrom to the exterior of the mill. 90
3. A colloid mill comprising in combination; relatively rotatable material treatment members positioned to form a material treatment passageway therebetween, wedge shaped annular projections formed thereon in concentric rows whereby annular wedge shaped troughs are formed between adjacent rows of the projections, the rows of projections of one member being matingly positioned in the troughs of the other member to form dispersion passageways therebetween, non-material dispersion passageways formed at the bottoms of the troughs communicating with the dispersion passageways for effecting a comparatively slow movement of the material therein as it is advanced from one dispersion passageway to another, means for rotatably supporting the members, means for rotating the members relatively, means for supplying material to the material treatment passageway for treatment, and means for conducting the treated material therefrom to the exterior of the mill. 100
4. A colloidal mill comprising in combination; relatively rotatable material treatment members positioned to form a material treatment passageway therebetween, tubular extensions formed thereon having orificed end portions, housing surrounding the orificed end portions arranged to effect a closure thereover, tubular members supported by the housings extending through the tubular extensions to the material treatment passageway arranged to supply material to the passageway for treatment, tubular members supported by the housings spacedly surrounding the material supply tubular members arranged to supply a heat exchange liquid adjacent the material treatment passageway and thence to the interior of the tubular extensions by flow thereof through the space formed between the tubular members, means for rotatably supporting the material treatment members, means for rotating the members relatively, means for supplying material to the material supply tubular members, means for supplying a heat exchange liquid to the heat exchange liquid supply tubular members, means for conducting the liquid from the tubular extensions, and means for conducting the treated material discharged by the treatment passageway to the exterior of the mill. 110
5. A colloid mill comprising in combination; relatively rotatable material treatment members positioned to form a material treatment passageway therebetween, tubular extensions formed thereon having orificed end portions, housings for rotatably supporting the orificed end portions having chambers therein arranged in communication with the orifices, housings supported by the orificed end portion housings having chambers therein arranged to receive a heat exchange liquid thereinto, means supported by the last named housings for conducting the liquid from the chambers therein adjacently to the material treatment passageway and thence through the orifices to the first named chambers, means for supplying a heat exchange liquid to the heat exchange liquid chambers, means for conducting the liquid from the first named chambers to the exterior of the mill, means for rotatably supporting the treatment members, means for rotating the members relatively, means for supplying material to the treatment passageway for treatment thereby, and means for conducting the treated material discharged therefrom to the exterior of the mill. 120
6. A colloidal mill comprising in combination; relatively rotatable material treatment members positioned to form a material treatment passageway therebetween, a material receiving chamber formed between the members positioned adjacent the material receiving end of the treatment passageway, rotatable chambered rotor members for supporting the treatment members having orifices communicating to the chambers therein, material supply members positioned within the chambers having the material receiving end portions thereof extending through and terminating exteriorly of the orifices and the discharge ends thereof arranged to discharge the material into the receiving chamber of the material treatment members, means for rotatably supporting the chambered rotor members, means for rotating the members relatively, means for supplying material to the material supply members for passage to the treatment passageway, and means for conducting the treated material discharged thereby to the exterior of the mill. 130
7. A colloidal mill comprising, a chambered rotor member having a heat exchange portion formed at one end thereof, a material treatment surface formed on the outer face of the heat exchange portion being arranged to rotate relatively to a correlated surface whereby a material treatment passageway is formed therebetween, a heat exchange surface formed in the inner face of the heat exchange portion positioned in communication with the rotor chamber, an annular deflecting member having a centrally disposed opening therein positioned in the chamber adjacent the heat exchange surface 140
- 75

- the chamber to the opening arranged to conduct the liquid from the chamber to the opening.
13. A colloidal mill comprising, co-axially disposed rotor members having abutting material treatment portions arranged to form a material treatment passageway therebetween and tubular portions joined thereto extending in opposite directions therefrom, a main housing member surrounding the material treatment portions, motor units surrounding the rotor members having the driving elements thereof secured to the tubular portions thereof for effecting the rotation thereof, ventilated housing members surrounding the rotor members engaging the main housing and the motor units, subsidiary housing members surrounding the outer ends of the tubular portions, ventilated housing members surrounding the rotor members engaging the motor units and the subsidiary housing members, and means supported by the housing members for rotatably supporting the rotor members.
14. The combination with a colloidal mill arranged to have one or more material treatment rotors thereof rotated by motor units connected to a source of energy, of thermostatic means positioned in the discharge flow of the material treated by the rotors affected by variation in temperature thereof normally connecting the source to the motor units arranged to effect a disconnection therefrom upon an abnormal increase of temperature of the material in the discharge flow.
15. The combination with a colloid mill having a heat exchange liquid supplied thereto for controlling the temperature of the material treatment surfaces of material treatment rotors supported thereby, the rotors being rotated by motor units connected to a source of energy, of thermostatic means positioned in the discharge flow of the liquid from the mill affected by variations in temperature thereof normally connecting the source to the motors arranged to effect the disconnection therefrom upon an abnormal increase in temperature of the discharge flow.
16. The combination with a colloidal mill having a heat exchange liquid supplied from a source thereto for controlling the temperature of the material treatment surfaces of the material treatment rotors supported thereby, of thermostatic means positioned in the discharge flow of the heat exchange liquid from the mill affected by variations in the temperature thereof for controlling the flow of the liquid from the source to the mill arranged to increase the flow of the liquid from the source to the mill upon an increase in the temperature of the discharge flow and decrease the flow from the source upon a decrease in the temperature thereof.
17. A colloidal mill comprising, relatively rotatable material treatment members arranged to abut one another, a concentric series of wedge shaped annular projections formed on the abutting faces of the members, the projections of one member being arranged to matingly enter between the projections of the other member, material treatment surfaces formed on the annular projections the surfaces being formed continuously circumferentially on the projections and the surface of one member being positioned relatively to the surfaces of the other member to form a series of highly restricted passageways between the inner and outer edges of the abutting faces whereby all the material to be treated is constrained to pass successively therethrough during the relative rotation of the members, means for rotatably supporting the members to rotate relatively, means for supplying material to the inner edge of the abutting faces for treatment in the restricted passageways, and means for conveying the treated material from the mill.
18. A colloidal mill comprising, co-axially disposed rotor members having abutting material treatment portions formed thereon, the abutting ends thereof forming a material treatment passageway extending between the inner and outer edges thereof, chambered portions formed on the rotor members rearwardly of the material treatment portions having a heat exchange liquid chamber therein, the chambered portions having openings in the outer ends thereof communicating with the chamber, a material receiving chamber formed between the abutting ends of the material treatment portions positioned at the inner end of the material treatment passageway, orifices formed in the material treatment portions adjacent the material receiving chamber, tubular members extending through the chambers of the chambered portions, the inner ends thereof being supported in the orifices of the material treatment portions and the outer ends thereof extending through the openings of the chambers and being supported independently of the rotor members, means for supplying material to the outer ends of the tubular members for flow to the material receiving chamber, means for supplying a heat exchange liquid to the chambers for thermally affecting the material in the tubular members and the material treatment passageway, means for rotating the rotor members relatively, and means for conveying the treated material discharged by the outer end of the material treatment passageway from the mill.
19. A colloidal mill comprising, co-axially disposed rotor members having abutting material treatment portions formed thereon, the abutting ends thereof forming a material treatment passageway extending between the inner and outer edges thereof, chambered portions formed in the rotor members rearwardly of the material treatment portions having a heat exchange liquid chamber therein, the chambered portions having openings in the outer ends thereof communicating with the chamber, a material receiving chamber formed between the abutting ends of the material treatment portions positioned at the inner end of the material treatment passageway, orifices formed in the material treatment portions adjacent the material receiving chamber, non-rotatable tubular members extending through the chambers of the chambered portions between the orifices of the material treatment portions and the openings of the chambered portions, the inner ends thereof communicating with the material receiving chamber, means associated with the orifices of the material treatment portions for rotatably supporting the inner ends of the tubular members therein, means for fixedly supporting the outer ends of the tubular members independently of the rotor members adjacent the openings of the chambered portions, means for supplying material to the outer ends of the tubular members for movement to the material receiving chamber, means for supplying a heat exchange liquid to the heat exchange chamber for thermally affecting the material in the tubular members and the material treatment passageway, means for rotating the rotor members relatively, and means for conveying the treated material

- discharged by the material treatment passageway from the mill.
20. A colloidal mill comprising, co-axially disposed rotor members having chambered material treatment portions formed on the abutting ends thereof, material treatment surfaces formed on the abutting ends arranged to form a material treatment passageway between the inner and outer edges thereof, cylindrical portions formed 5 on the rotor members having one end of the bores therein communicating with the chambers of the material portions and an opening formed at the other ends thereof, a heat exchange portion formed on the abutting ends between the material treatment surfaces and the chambers for effecting heat transfer therebetween, a material conveying member extending through the chamber and the bore having the inner end thereof communicating with the inner end of 10 the material treatment passageway through the heat exchange portion and the outer end thereof extending through the openings in the bore, means for circulating a heat exchange liquid in the chamber in contact with the heat exchange portion and the material conveying member, means for effecting a flow of material through the material conveying member to the material 15 passageway for treatment therein, and means for rotating the rotor members relatively for treating the material in the passageway.
21. A colloidal mill comprising, co-axially disposed rotor members having material treatment surfaces formed on the abutting ends thereof arranged to produce a material treatment passageway between the inner and outer edges thereof, inner bearing members surrounding the rotor members positioned adjacent the abutting ends thereof, outer bearing members surrounding the rotor members positioned adjacent the outer ends thereof, means for supporting the bearing members for rotatably supporting the rotors in axial alignment, a rotating motor element surrounding the rotor member positioned between the inner and outer bearing members, the element being 30 rigidly secured to the rotor members for effecting rotation thereof, motor stator elements spacedly surrounding the rotating motor elements, one of the stator elements being arranged to inductively rotate the rotor element correlated thereto in a direction oppositely from the rotation of the other rotor member, a base member for fixedly supporting the motor stator elements in inductive relation to the rotor elements, and means supported by the base member for supporting the bearing supporting members.
22. A colloidal mill for dispersing one material into another comprising co-axially disposed adjacently positioned chambered rotor members having dispersion surfaces formed on abutting end portions thereof arranged to form a dispersion passageway therebetween, a material receiving chamber formed between the abutting end portions communicating with the entrance end of the dispersion passageway, a passageway formed 45 in one rotor member extending from the free end portion thereof to the receiving chamber arranged to conduct one material to the chamber, another passageway formed in the other rotor member extending from the free end portion thereof to the receiving chamber for conducting another material to the receiving chamber, means for effecting a flow of heat exchange liquid in the chambers of the rotor members, the inlet and outlet of the heat exchange chambers in the rotors being concentric with and parallel to the 50 material inlet, means for supplying the materials to the passageways through the free end portions of the rotor members to their respective passageways, means for rotating the rotor members relatively for dispersion of the materials in the dispersion passageway, and means for conveying the dispersed materials from the mill.
23. A colloidal mill comprising, co-axially disposed rotor members having material treatment surfaces formed on the abutting ends thereof arranged to produce a material treatment passageway therebetween, a housing surrounding the rotor members, bearings surrounding the rotor members positioned adjacent the abutting ends thereof, bearing supporting housings surrounding the bearings supported by the rotor housing, the bearing supporting housings being removable therefrom but normally rigidly secured therein, thrust bearing units surrounding the rotor members supported by the bearing supporting housings, certain thrust elements of the units being rigidly secured to the rotor members and the other thrust elements thereof being supported by the unit, the unit being axially adjustably supported by the bearing supporting housings whereby axial adjustment thereof will vary the size of the material treatment passageway, means for supplying material to the material treatment passageway through the rotor members, and means for effecting relative rotation of the members for treating the material in the passageway.
24. A colloidal mill comprising, co-axially disposed relatively rotatable rotor members having material treatment surfaces formed on the abutting end portions thereof arranged to form a material treatment passageway therebetween, the abutting end portion having a heat exchange liquid chamber formed therein arranged to effect heat exchange of the material treated in the material treatment passageway, tubular portions 110 formed rearwardly of the abutting end portions having one end of the bore therein communicating with the chambers and openings formed in the other ends thereof, a fixed housing surrounding the outer end of each tubular portion, the housing having a heat exchange liquid discharge chamber therein communicating with the opening in the bore, a heat exchange liquid receiving chamber formed in the housing, a tubular member extending spacedly through the bore, the member having the outer end thereof communicating with the liquid receiving chamber and the inner end thereof communicating with the liquid chamber of the abutting end portion, and means for supplying a heat exchange liquid to the receiving 115 chamber for effecting flow thereof through the tubular member to the heat exchange chamber of the abutting end portion for effecting heat transfer of the material in the material treatment passageway and thence through the space in the bore to the receiving chamber through the opening of the bore, means for conveying the liquid received by the receiving chamber from the mill, means for supplying material to the material treatment passageway for treatment thereby, and means for rotating the rotor members relatively for treating the material in the passageway.
25. A colloidal mill comprising, co-axially disposed relatively rotatable rotor members having chambered abutting portions, the abutting ends thereof having material treatment surfaces formed thereon arranged to produce a material treatment passageway therebetween, tubular portions 125 formed on the rotor members rearwardly of the abutting portions having material treatment surfaces formed thereon arranged to produce a material treatment passageway therebetween, the abutting ends of the tubular portions having material treatment surfaces formed thereon arranged to produce a material treatment passageway therebetween, tubular portions 130 formed on the rotor members rearwardly of the abutting portions having material treatment surfaces formed thereon arranged to produce a material treatment passageway therebetween, the abutting ends of the tubular portions having material treatment surfaces formed thereon arranged to produce a material treatment passageway therebetween, tubular portions 135 formed on the rotor members rearwardly of the abutting portions having material treatment surfaces formed thereon arranged to produce a material treatment passageway therebetween, the abutting ends of the tubular portions having material treatment surfaces formed thereon arranged to produce a material treatment passageway therebetween, tubular portions 140 formed on the rotor members rearwardly of the abutting portions having material treatment surfaces formed thereon arranged to produce a material treatment passageway therebetween, the abutting ends of the tubular portions having material treatment surfaces formed thereon arranged to produce a material treatment passageway therebetween, tubular portions 145 formed on the rotor members rearwardly of the abutting portions having material treatment surfaces formed thereon arranged to produce a material treatment passageway therebetween, the abutting ends of the tubular portions having material treatment surfaces formed thereon arranged to produce a material treatment passageway therebetween, tubular portions 150 formed on the rotor members rearwardly of the abutting portions having material treatment surfaces formed thereon arranged to produce a material treatment passageway therebetween, the abutting ends of the tubular portions having material treatment surfaces formed thereon arranged to produce a material treatment passageway therebetween.

- of the chambered portions having the inner ends of the bores therein communicating with the chambers and the outer ends of the bore open ended, a main housing surrounding the abutting portions of the rotor members having bearings supported therein for rotatably supporting the inner ends of the rotor members, subsidiary housings surrounding the tubular portions adjacent the openings therein, the last named housings having bearings for rotatably supporting the outer ends of the rotor members, motor units surrounding the tubular portions having the driving elements thereof rigidly secured to the rotor members the motor units being positioned between the bearing housings, a base member for supporting the main and subsidiary housings and the stationary elements of the motor units, means for supplying material to the material treatment passageway through the subsidiary housings and means for supplying a heat exchange liquid to and from the chambers of the abutting portions through the subsidiary housings independently of the means for supplying the material therethrough to the material treatment passageway therethrough. 5 10 15 20 25
26. A colloidal mill comprising, a rotor member having a chambered portion, the chambered portion having a material treatment surface formed on one end thereof arranged to abut a correlated material treatment surface whereby a material treatment passageway is formed therebetween, a tubular portion formed on the rotor member having the inner end thereof integrally joined to the outer end of the chambered portion, the outer end of the tubular portion having an opening therein communicating with the bore thereof, the bore communicating with the chamber of the chambered portion, a fixed housing member surrounding the outer end of the tubular portion having a chamber therein communicating with the opening of the tubular portion, means associated with the housing member for effecting a flow of heat exchange liquid to the rotor chamber through the opening of the tubular portion and thence to the chamber of the housing, and means associated with the housing for conducting the liquid from the chamber therein. 30 35 40 45 50
27. A colloidal mill comprising, co-axially disposed rotor members having abutting chambered end portions, material treatment surfaces formed on the abutting ends thereof arranged to produce a material treatment passageway between the inner and outer edges thereof, tubular portions formed on the rotor members rearwardly of the chambered portions having the bores thereof communicating with the chambers, openings formed in the outer ends of the tubular portions, a material receiving chamber formed between the abutting ends of the rotor members positioned at the inner end of the material treatment passageway, tubular members extending spacedly through the chambers and the bores having the inner end portions thereof communicating with the material receiving chamber and the outer end portions thereof extending spacedly through the bore of the tubular portions to the openings thereof, means for supplying materials to the outer end portion of the tubular members for delivery to the material receiving chamber to be treated by the material treatment passageway, means for supplying a heat exchange liquid to and from the chambers of the end portions, means for rotating the rotor members relatively for treating the materials in the passageway, and
- means for conveying the treated material discharged by the material treatment passageway from the mill. 55 60 65 70 75
28. A colloidal mill comprising, a rotor member having a comparatively large diameter chambered material treatment portion formed at one end thereof, a material treatment surface formed thereon arranged to rotate relatively to a correlated material treatment surface whereby a material treatment passageway is formed therebetween, a tubular shaft portion formed rearwardly of the material treatment portion having a diameter less than the material treatment portion, the shaft portion being integrally joined to the material treatment portion and the bore therein communicating with the chamber therein, a bearing member for rotatably supporting the rotor member surrounding the shaft portion thereof in juxtaposition to the material treatment portion thereof, another bearing member for rotatably supporting the rotor member surrounding the free end of the shaft portion, a motor unit surrounding the shaft portion positioned between the bearing members, the rotating element of the motor unit being rigidly secured to the shaft portion, a duct extending axially through the rotor member for supplying materials to the material treatment passageway, means for supplying material to the duct, means for supplying a heat exchange liquid to the chamber through the bore of the shaft portion, and a horizontally disposed base member arranged to support the bearing members, and the stationary element of the motor unit. 80 85 90 95 100 105
29. A colloidal mill comprising, co-axially disposed oppositely facing rotor members having material treatment surfaces formed on the abutting ends thereof arranged to produce a material treatment passageway therebetween, a main housing surrounding the abutting ends of the rotor member arranged to receive the materials discharged by the material treatment passageway, bearing members supported by the housing for rotatably supporting the rotor members positioned adjacent the abutting ends thereof, subsidiary housings surrounding the free ends of the rotor members having bearings supported therein for rotatably supporting the free ends of the rotor members, motor units surrounding the rotor members positioned between the main and subsidiary housings having the driving elements thereof rigidly secured to the rotor members, a base member for supporting the stationary elements of the motor units and the main and subsidiary housings, auxiliary housings supported between the main housing and the motor units independently of the base member, and other auxiliary housings supported between the motor units and the subsidiary housings independently of the base member. 110 115 120 125 130 135
30. A colloidal mill comprising, horizontally disposed oppositely facing rotor members having material treatment surfaces formed on the abutting ends thereof whereby a material treatment passageway is formed therebetween, a base member, a plurality of axially disposed end connected housing members completely surrounding the rotor members for enclosing all rotating parts thereof are enclosed within the housings, certain housings comprising stationary elements of motor units supported by the base for rotating the rotor members, conduits for conveying a heat exchange liquid to and from the rotor members connected to certain of the housing members, other conduits for conveying materials 140 145 150

- to be treated by the material treatment passageway connected to certain other housings, and a conduit for conveying the treated material from the mill connected to another certain 5 housing, the liquid and material conduits extending downwardly from the housings below the base member whereby the portion of the mill thereabove is unobstructed.
31. A colloidal comprising, relatively rotatable 10 material treatment members arranged to abut one another, a concentric series of wedge shaped annular projections formed on the abutting faces of the members, the projections of one member being arranged to matingly enter between the 15 projections of the other member, material treatment surfaces formed on the annular projections the surfaces being formed continuously circumferentially on the projections and the surfaces of one member being positioned relatively to the 20 surfaces of the other member to form a series of highly restricted passageways between the inner and outer edges of the abutting faces, a concentric series of grooves formed on the abutting faces of the rotor members alternately with the 25 projections thereon arranged to form comparatively free passageways whereby all the material is constrained to pass through the highly restricted passageways alternately with passing through the comparatively free passageways 30 during the relative rotation of the rotor members, means for rotatably supporting the members to rotate relatively, means for supplying material to the inner edges of the abutting faces for treatment in the restricted passageways, and means for 35 conveying the treated material from the mill.
32. A colloidal mill comprising, co-axially disposed rotor members having abutting material treatment portions formed thereon, the abutting ends thereof forming a material treatment passageway extending between the inner and outer 40 edges thereof, chambered portions formed on the rotor members rearwardly of the material treatment portions having a heat exchange liquid chamber therein, the chambered portions having openings in the outer ends thereof communicating with the chamber, a material receiving chamber formed between the abutting ends of the material treatment portions positioned at the inner end of the material treatment passageway, orifices formed in the material treatment 45 portions adjacent the material receiving chamber, material conveying passageways extending through the chamber of the chambered portions between the orifices of the material treatment portions and the openings of the chambers in the chambered portions, means for supplying material to the material conveying passageways for movement to the material receiving chamber, means for supplying a heat exchange liquid 50 to the chambers through the openings thereof, means for rotating the rotor members relatively, and means for conveying the treated material discharged by the material treatment passageway from the mill.
33. A colloidal mill comprising, co-axially disposed rotor members having the inner end portions thereof formed with abutting material treatment surfaces arranged to produce a material treatment passageway therebetween, chambered portions formed rearwardly of the inner end portions having openings therein positioned at the outer ends of the rotor members, bearing members surrounding the rotor members for 55 rotatably supporting the members in axial alignment, motor units surrounding the rotor 60 members having the driving elements thereof rigidly secured thereto for effecting rotation thereof and the stationary elements of the units fixedly positioned in inductive relation to the driving elements thereof, means for supplying a heat exchange liquid to the chambers of the rotor members through the openings therein, ducts extending through the chambers between the openings therein and the material treatment passageway for conveying materials to be treated 65 therein, and means for supplying materials to the ducts for movement to the material treatment passageway.
34. The combination with a colloid mill operated by a motor connected to a source of energy, 70 the mill having a heat exchange liquid flowing therethrough for thermally affecting the material being dispersed thereby, of means for conveying the heat exchange liquid to the mill, means for conveying the heat exchange liquid 75 from the mill, and means associated with the heat exchange discharge conveying means affected by the discharge flow therein normally effecting supply of energy from the source to operate the motor arranged to cancel the supply 80 therefrom upon a predetermined rise in the temperature of the liquid discharge flow.
35. The combination with a colloid mill having means for conveying the materials treated thereby from the mill, the mill having a heat exchange liquid supplied thereto for thermally affecting the material treated therein, of means associated with the treated material conveying means affected by the variation in temperature of the treated material flowing therein arranged 85 to vary the quantity of the heat exchange liquid supplied to the mill substantially in proportion to the variation in the temperature of the treated material discharged by the mill.
36. A colloidal mill comprising, a rotor member having a material treatment surface formed on one end thereof arranged to rotate relatively to a correlated material treatment surface for forming a material treatment passageway therebetween, ball bearings surrounding the rotor 90 member positioned adjacent each end thereof with respect to the axis of rotation of the rotor member, the bearings having the inner races thereof rigidly secured for rotation with the rotor member and the outer races thereof supported 95 slidably axially with respect to the axis of rotation of the rotor member, a thrust bearing unit surrounding the rotor member spacedly between the ends thereof, the unit being positioned inwardly adjacent the ball bearing adjacent the 100 material treatment surface end of the rotor member, a normally rotating portion formed on the unit rigidly secured to the rotor member for rotation therewith, a rotatively supported normally stationary portion formed on the unit co- 105 operating with the normally rotating portion thereof for controlling the axial movement of the rotor member, the normally stationary portion being arranged to effect axial rotation of the rotor member for varying the size of the material treatment passageway upon variable rotation thereof, means for effecting variable rotation of the normally stationary portion of the thrust bearing unit, and means for rotating the 110 rotor member positioned between the thrust bearing unit and the bearing adjacent the end opposite to the material treatment surface end of the rotor member.
37. A colloidal mill comprising, a rotatively supported rotor member having a material 115

treatment surface formed on one end thereof arranged to abut a correlated material treatment surface for forming a material treatment passageway therebetween, means rotatively supporting the rotor member permitting axial movement thereof, a thrust bearing unit surrounding the rotor member having a normally stationary rotatively supported portion and a normally rotating portion co-operating therewith 5 rigidly secured to the rotor member for rotation therewith, the rotation of the normally stationary portion being arranged to effect axial movement of the rotor member for varying the size of the material treatment passageway, a 10 manually operated rotatively supported gauging member having means associated therewith arranged to indicate the size of the material treatment passageway as the member is rotated, and reduction gearing connected between the gauging member and the normally stationary portion of the unit arranged to effect rotation of the normally stationary portion upon rotation of the gauging member, the increment of rotation of the normally stationary portion being comparatively small as compared to the increment of 15 rotation of the gauging member whereby minute adjustments in size of the material treatment passageway may be made.
